UNITED STATES PATENT OFFICE

161,394

FIREDOG

Ephraim C. Sooy, Kansas City, Mo.

Application March 13, 1950, Serial No. 8,501

Term of patent 7 years

(Cl. D81—6)

To all whom it may concern:

Be it known that I, Ephraim C. Sooy, a citizen of the United States, residing at Kansas City, in the county of Jackson and the State of Missouri, have invented a new, original, and ornamental Design for a Firedog, of which the following is a specification, reference being had to the accompanying drawing, forming a part thereof.

Fig. 1 is a side elevation of a firedog, showing my new design.

Fig. 2 is a plan view of the firedog,

Fig. 3 is a rear end elevation, and

Fig. 4 is a front end view of the firedog.

I claim:

The ornamental design for a firedog, as shown.
EPHRAIM C. SOOY.
